G. BRIGHT.

GATEWAY OR ENTRANCE FOR CEMETERIES.

No. 17,166.

Patented Mar. 8, 1887.

UNITED STATES PATENT OFFICE.

GEORGE BRIGHT, OF ST. LOUIS, MISSOURI, ASSIGNOR TO KRABBE, ESPEN-SCHIED & BRIGHT, OF SAME PLACE.

DESIGN FOR A GATEWAY OR ENTRANCE FOR CEMETERIES.

SPECIFICATION forming part of Design No. 17,166, dated March 8, 1887.

Application filed January 25, 1887. Serial No. 925,486. Term of patent 7 years.

To all whom it may concern:

Be it known that I, GEORGE BRIGHT, a citizen of the United States, residing at St. Louis, in the State of Missouri, have invented and produced a new and original Design for Posts for Entrances and Corners of Burial Lots in Cemeteries; and I do hereby declare the following, when taken in connection with the accompanying photographic illustration and the letters of reference marked thereon, to be a full, clear, and exact description of the same, and which said illustration constitutes part of this specification.

Figure 1 is a front elevation of an entrance, with my newly-designed post shown at each side. Fig. 2 is an elevation of my newly-designed corner-post, both entrance and corner posts, however, belonging together, and constituting the whole design.

This invention relates to a design for entrance and corner posts for burial lots in cemeteries; and it consists in the peculiar outline of the posts and configuration of the parts or members, as more fully hereinafter described.

The entrance post or posts, Fig. 1, consist of an upper and lower part, the lower part being the post proper and the upper part being an urn. The design of the post is round, and includes all that portion of it above the base A, and is provided with scallops a, members b, and is checked at c. On top of this post is placed an urn of the design shown in the

photograph, the bowl of which has leaves d carved on it below and an ivy-vine, e, entwined around its rim.

The corner-post, Fig. 2, consists of the original outline shown, and includes all that portion of it above the base A', and has, first, the scallops f; above these the panels g, then the members h; above these the scallops i, and finally, the reeds k at the top.

The buttress-posts B for the entrances are the same in outline and design as the corner-posts, and are fac-similes of same, only smaller.

What I claim is—

1. In a design for a gateway or entrance, the entrance-posts having scallops a, members b, and checks c, substantially as herein shown and described, and surmounted with an urn or vase, as set forth.

2. In a design for a gateway or entrance, the entrance-posts having scallops a, members b, checks c, and an urn the bowl of which has leaves d carved on it below and an ivy-vine, e, entwined around its rim, substantially as herein described and shown.

3. In a design for a gateway or entrance, the corner-post having scallops f, panels g, members h, scallops i, and reeds k, substantially as herein described and shown.

GEORGE BRIGHT.
